Application July 22, 1946, Serial No. 685,443

12 Claims. (Cl. 226—81)

1

The present invention relates to container sealing apparatus. The invention is a continuation-in-part of my original application Serial No. 371,961 for Apparatus for Sealing Containers, filed December 27, 1940, now Patent No. 2,408,447, issued October 1, 1946.

An object of the invention is to provide a container sealing apparatus which will occupy a minimum of floor space.

Prior container sealing apparatus, and particularly those which include a steam chamber, occupy a comparatively long area. One purpose in providing a long steam tunnel has been to form a long enclosed area at each end of the critical cap applying and sealing points, with a view of isolating these points from outside air and obtaining high temperature at least at such points. Some types of such apparatus have been provided with capping elements of endless type and it has been thought desirable to have at least a substantial portion of the same enclosed by the tunnel, particularly since the element might induce drafts in the upper portion of the tunnel. By the present invention, the use of a longitudinally moving sealing element is avoided, so that the tunnel need not be extended to enclose such a device.

Use of a short tunnel, with its lower portion clear of steam, as described in my said original application, permits each container to be constantly visible. This is a highly desirable feature particularly during the initial portion of a run when it is necessary to ascertain whether the cap applying and sealing adjustments are correct.

The principal purpose of providing a lengthwise moving capping element has apparently been to enable the containers to move continuously during the sealing operation. While this procedure theoretically gives high production, the sealing action afforded thereby is not always satisfactory, particularly when handling caps provided with holding lugs upon their skirts. Also, containers may be upset or any type of cap may be bent or dislodged when it first comes into contact with the sealing element as well as when it finally moves out of contact with the element. This is particularly true if there is the slightest slippage of the upper capping belt with respect to the lower container supporting belt, or if the container slips with regard to either belt.

I have found that a high rate of production with completely uniform sealing can be obtained by stopping the containers in order to seal the same. The high rate of satisfactory production

2

obtained is due to the fact that there is less likelihood of containers being upset during the sealing action, with resultant long stoppages to clear out the spilled contents, and also because no containers need be discarded and returned through the machine because of improperly applied caps. At the same time, the arrangement of the present invention occupies a minimum floor space. It is also to be noted that the use of a sealing head of non-continuous type contributes to a more efficient and uniform vacuum effect within the containers because of certain factors hereinafter discussed in connection with the operation of the device.

15 Another object of the invention is to provide a capping element which is particularly adapted for the quick and proper sealing of containers.

A further object of the invention is to provide a control for a capping mechanism which is actuated by contact of a container therewith. Such an arrangement is highly desirable because it eliminates the necessity of moving containers through the machine in carefully spaced relation.

20 Another object of the invention is to provide a container actuated capping control of such design as to insure that the container will be stationary when the sealing is performed, thereby making it certain that every type of cap will be properly sealed and not damaged and that a high net rate of production will be obtained.

One reason why container sealing machines of the present type have heretofore been provided with continuously moving sealing elements was because it was thought that any stoppage of the containers to seal the same might cause the containers to be upset, or their contents to be so disturbed that some portion thereof would be spilled. It has been found that the present invention, involving moving the container onto a stationary support while its upper portion is gripped, prevents upsetting and causes no spilling of containers filled to the customary levels. Also, by stopping the containers to seal the same, all of the disadvantages of a continuously movable sealing element are eliminated and every type of cap can be efficiently sealed upon containers. As has been stated above, the continuous system is only efficiently applicable with certain types of caps.

25 Still another object of the invention is to provide a container holding and centering arrangement which is adapted to engage the containers while caps are being applied thereto.

30 As has been hereinbefore indicated, consider-

able difficulty has been experienced in prior capping machines because containers were frequently upset upon contact with the cap applying device. By the present invention, the containers are securely held at the time that they come into contact with the cap applying mechanism, all possibility of the containers falling over being thereby eliminated.

Another object of the invention is to provide a holding mechanism which is simple in construction, will smoothly and efficiently engage and center containers, and which is readily adjustable for containers of various sizes and shapes.

Another object of the invention is to provide a cap applying and sealing arrangement which includes means to properly level caps upon containers immediately prior to the sealing action.

Other objects and advantages of the invention will be apparent from the following drawings, wherein:

Figure 1 is a side elevation of the central portion of an apparatus such as disclosed in said original application, with parts broken away.

Figure 2 is a detail view showing a sealing head control mechanism.

Figure 3 is a horizontal sectional view on the line 3—3 of Figure 6, but on a larger scale.

Figure 4 is a section on the line 4—4 of Figure 5.

Figure 5 is a front view of a sealing head control mechanism.

Figure 6 is an end view of a container centering element, the view being taken on the line 6—6 of Figure 1.

Figure 7 is a horizontal section on the line 7—7 of Figure 6.

Figure 8 is a diagrammatic view of a capping head controlling circuit, and

Figure 9 is a diagrammatic view of a second capping control and the circuit therefor.

The structure of the present invention is hereinafter described in connection with a container sealing apparatus such as disclosed in my above-mentioned original application, Serial No. 371,961 and the patent thereon. The general arrangement and operation of the present invention in connection with such an apparatus may be generally described as follows: The numeral 10 designates the table of the original application apparatus along which a continuously moving endless conveyor 11 travels. A chamber or tunnel 12 extends above the table 10 and a steam atmosphere may be maintained within the tunnel by steam flowing from a supply duct 13 as described in said original application.

Containers C moving through the apparatus enter at the left hand end of Figures 1 and 3 upon the endless belt or conveyor 11 and are continued past the steam duct 13 which maintains a quiet cloud of steam in the upper portion of the tunnel. As a container moves past the duct 13 its upper portion comes into contact with the belts 16 of a container centering device 17 (Figure 1). As is best shown in Figure 6, upper and lower belts 16 are provided on each side of the path of movement of the containers so that the containers will be held upright by the belts. The belts 16 move at the same speed as the conveyor 11. Immediately after a container has moved into engagement with the centering device 17 the leading edge of the mouth of the container will contact with the lowermost cap C' in a cap chute or cap applying means 18 and the continuing movement of the container will cause this cap to be withdrawn from the chute and dropped to

a loosely applied position upon the mouth of the container.

As soon as a cap C' has been substantially removed from the chute 18, its upper portion will come into contact with the forward edge of a plate 19 resiliently mounted upon and forming part of the capping plate or member 20. Plate 19 will level the cap upon the container mouth.

As is indicated in Figure 1, while the above cap leveling action is taking place, the base of the container will be moving onto a fixed support plate 21 forming part of the table 10 of the apparatus. Also, the lower portion of the container will then come into contact with a trip device 22 which is shown in top plan in Figure 3. As the movement of the container with conveyor 11 and holding device 17 continues, the container will force the trip device 22 laterally out of its path. Laterally adjustable guide rails 22a will prevent the container from moving laterally.

As the forward movement of the container stops, because its base has moved entirely off conveyor 11 to stand entirely upon plate 21 as indicated in Figure 3, and also because its upper portion has moved out of contact with the holding device 17, trip 22 will be forced laterally from the position illustrated in Figure 3 to cause a switch device such as shown in Figure 2 or Figure 5 to actuate the delayed action electrical circuit diagrammatically shown in Figure 8. When the Figure 8 circuit is finally completed, as herein-after described, and by which time all movement of the container will have ceased, the electromagnet 24 shown encased in Figure 1 and diagrammatically shown in Figure 8 will be energized so that the capping plate 20 will move downwardly to compress the light springs above plate 19. As a result, the loosely applied cap will be forced to a sealed position upon the stationary container. When the capping member 20 has moved downwardly the proper distance, a limit switch 25 will be opened to de-energize the electromagnet 24. Springs 26 will then lift the capping head 20 so as to leave the container standing free upon the fixed plate 21.

Contact of the succeeding container with the container shown in Figure 3 will position the latter off the plate 21 and upon the outfeed portion of endless conveyor 11. It will be noted from Figure 1 that the upper run of conveyor 11 dips down beneath the stationary plate or support 21.

As is described in said original application, during the movement of the container through the steam chamber 12, and before a cap is applied thereto, the head space of the container can be filled with steam from the cloud of steam present in the upper portion of the chamber. After the container has been sealed, as just described, it will move from the chamber through a gradually decreasing cloud of steam so that the steam entrapped in the head space will condense to create a low pressure condition therein which will assist in holding the cap in sealed position.

Referring to the structure of the present invention in detail, Figures 6 and 7 illustrate the manner in which the container centering and holding device 17 is mounted in the opposite side walls 31 of the tunnel or chamber 12. Referring to these figures, each belt 16 is supported in a U-shaped bracket 32 which includes two longitudinally spaced pins 33 and 34. The pin 33 is slidable in a bore formed in a plate 35 which closes a large rectangular opening in the corresponding side wall 31 of the steam chamber. As best shown in Figure 7, the other pin 34 is slidable

in a hollow sleeve 37 threaded in the plate 35. The inner end of each sleeve 37 is counter-bored and a coil spring 38 surrounding the pin 34 is seated in this counter-bore. The position of each bracket 32 with respect to the center line of the container supporting conveyor 11 may be adjusted inwardly by rotation of the holding wheel 39 fixed to each threaded sleeve 37, because the sleeve will act upon the coil spring 38 to force the bracket 32 inwardly by a straight line of rectilinear movement. The belts 16 can be moved outwardly by pressure upon the same and, because of their resilient mounting, will accommodate themselves to variations in containers C.

The holding and centering device 17 may be adjusted longitudinally of the machine by releasing the bolts 40 (Figure 7) which extend through slots to hold the plates 25 to the side walls of the chamber 12.

Each U-shaped bracket 32 includes a rear wall 45, a lower wall 46 and an upper wall 47. As shown at the bottom of Figure 7, each lower wall 46 is cut away at its infeed end. The outfeed end of each bracket has journaled therein a vertical shaft 50 to which is fixed, between the upper and lower plates 46 and 47, a pulley 51. An idler pulley 52 is supported on a stud 53 at the infeed end of each bracket and the belts 16 move about these pairs of pulleys. The inner run of each belt 16 is supported or held inwardly with respect to the center line of the machine by small idler rolls 54 positioned in the brackets 32. As best illustrated in Figure 7, the series of rolls 54 does not extend entirely to the infeed end of a bracket 32 and because of this, as well as because of the fact that the infeed end pulley 52 is of reduced diameter, each belt 16 will have the infeed portion of its inner run slightly inclined so as to assist in the centering action of containers. However, it will be noted that the remaining portion of the inner run of each holding belt is positively held straight by the small rolls so that a uniform pressure will be applied to containers during their movement with such portion of the belts.

It will likewise be noted that each belt 16 and its supporting bracket 32 is resiliently mounted, as an entirety, for inward and outward movement. That is, as a container causes the holding belt to be forced outwardly to a slight extent through the side wall of the steam tunnel, that holding belt and its supporting bracket 32 will move bodily outwardly along a straight line and with no swinging movement.

As best indicated in Figures 1 and 7, each shaft 50 carrying a driven pulley 51 of the holding device 17 has a sprocket wheel 58 fixed thereto which is engaged by a sprocket chain 59 extending from the outfeed end of the steam tunnel and about a large sprocket wheel 60 fixed to a vertical shaft 61 journaled in brackets 62 extending from the upper portion of the side walls of the steam chamber. The shafts 61 are driven from the same source of power as conveyor belt 11.

The cap supply and applying chute 18 preferably comprises two spaced guideways 65, each of well-known angular form to provide a shelf to support one edge of the cap and a shoulder to guide the cap. The major portion of the chute is surrounded by a casing which may include an electric heater. The guideways 65 terminate in lugs or shoulders 66 of well-known form which serve to stop the downward movement of the line of caps. As indicated in Figure 1, the lower portion of the skirt of the lowermost cap will bear

against these shoulders with the intermediate unsupported portion of the skirt extending into the path of the lip of an advancing container. As a result, the container will lift the cap over the shoulders 66 so that it will drop to a substantially leveled position on the container mouth, the succeeding cap then dropping down against the shoulders 66. The movement of a cap from its substantially vertical position in the chute to a substantially horizontal position without sidewise tilt is assisted by roller 67 journaled at the lower end of a weighted plunger 68 slidably mounted in an aperture in the upper wall of the steam chamber.

During its leveling movement the top of the cap is also continually engaged by the spring plate 19 of the capping device. Plate 19 includes upwardly extending studs 69 which fit in sockets in the capping plate 20 to thereby guide the vertical movement of plate 19. Plate 19 is urged to the normal downward limit position illustrated in Figure 1 by relatively light coil springs 70, one of which is positioned between each corner of plate 19 and the corresponding corner of the capping plate 20. It will be noted that the infeed end of plate 19 is beveled to guide the caps beneath the plate.

The above cap applying arrangement including the roller 67 and plate 19 serves to loosely apply all caps in a substantially level position without possibility of the cap dropping from the container. A particularly desirable feature is that the cap is firmly held from the moment that it leaves the chute 18 until it is finally sealed.

Referring to Figure 1, the capping member or plate 20 is mounted on the top wall of the tunnel immediately adjacent the cap applying chute 18 and is rigidly fixed to a pair of rods 76 extending through apertures in the top wall of chamber 12. The rods 76 are secured at their upper ends to a bar 77, this portion of each rod being threaded to receive nuts to bear on the upper and lower surfaces of bar 77 so that its position with respect to the rods can be adjusted. Intermediate its length each rod 76 is provided an adjustable collar 28a and a coil spring 28 is positioned between each such collar and the upper wall of the steam chamber. These springs serve to urge the rods and thereby capping plate 20 to an upward position.

A plunger 79 is fixed to the bar 77 and carries a plate 79a which is urged to an upward position by a coil spring 80. The upper surface of plate 79a is adapted to contact with round disks 81 rotatable on pins 82 and within a cut-out portion 83 of a lever 84. Plunger 79 extends through the cut-out and between the disks. The lever 84 has one end pivoted as indicated at 85 to a post 86 and the other end of the lever is pivotally connected as at 87 to a vertical link 88 pivoted to the armature 89 of electromagnet 24.

It will be noted that downward movement of armature 89 will cause the disks 81 to act upon spring mounted plunger 79 and thereby depress the capping plate 20. The upper spring 80 will serve as a resilient connection to compensate for containers of slightly greater than normal height and the lower springs 28 will serve to return the capping plate 20 to normal position.

As shown in Figure 3, the container-contacted trip 22 for the capping member 20 is of toggle form and comprises a lever 91 pivoted at 92 to the stationary plate 21 and carrying a roller 93 at its free end. Also, the free end of lever 91 is pivotally connected to a lever 94 pivoted to a long link 95 which is suitably held against other

than substantially longitudinal movement. As shown in Figure 3, the point at which arm 94 is connected to link 95 may be adjusted by a nut engaging a slot 96 in the link. The far end of link 95 is pivoted to one arm of a bell crank 97, the other arm of the bell crank having a link 98 extending therefrom to a casing 99 secured to the machine base and enclosing a switch device 23 such as shown in detail in Figures 4 and 5, or the switch device 23a shown in Figure 2.

Referring to the switch device 23 shown in Figures 4 and 5, link 98 may include a turnbuckle and extends through an aperture in the side wall of the housing 99 for the device 23. Within the housing, the rod 98 has a block 100 fixed thereto and the rod is urged to the right as viewed in Figure 5 by a coil spring 101 which surrounds the rod between the far wall of the housing and block 100. Block 100 carries a swinging pawl 103 which normally hangs downwardly alongside a vertical shoulder 104 on the block 100 as shown in Figure 5 and has its lower face 105 inclined. A block of insulating material 106 is positioned in the lower portion of housing 99 by means of screws and a pair of spring blades 108 and 109 are mounted on upper stepped faces of block 106 by means of screws 110 and 111, respectively, which also serve as binding posts for the contacts. The spring blades 108 and 109 carry contacts at their free ends and are normally in the separated position illustrated in Figure 5, this position being controlled by the adjusting screws 112 and 113.

In the operation of the switch device 23, as a container is moved from the infeed portion of supporting conveyor 11 to the position on the stationary plate 21 indicated in Figure 3, the forward and lower portion of the container will engage the roller 93 of trip 22 to move the toggle mechanism towards straightened position. As a result, the long link 95 will move to the right with regard to Figure 3, thereby moving the link 98 to the left in Figure 5. Such movement of link 98 will carry the block 100 to the left so that the point of pawl 103 will contact with a triangular nub 114 which extends upwardly from the upper contact blade 108, depressing this plate so as to bring its contact into engagement with the upwardly facing contact on lower blade 109 to cause a circuit to be actuated as hereinafter described. Rod 98 will continue its movement to the left in Figure 5 so that pawl 103 will continue past the nub 114 to permit the blade 108 to rise so that only a momentary electrical current will flow between the contacts carried on the blades.

The container will remain in the stationary position indicated in Figure 3 until the succeeding container contacts with it to move it from the stationary plate 21 to the outfeed portion of conveyor 11 and the pawl 103 will remain on the left hand side of the nub 114 while the container is in this position. When the container shown in Figure 3 moves to the right to enable the toggle mechanism to resume its normal position in the path of the next container, rod 98 will return to the Figure 5 position causing pawl 103 to ride over the nub 114. However, because the right hand face of pawl 103 is inclined and pawl 103 is free to swing in a clockwise direction, it will simply ride over nub 114 without depressing the spring blade 108. Hence, the contact element of blade 108 will not come into engagement with the contact of lower blade 109 during return movement.

Figure 8 shows the control circuit of the mech-

anism whereby the closing of the contacts of the switch device 23 of Figures 4 and 5 will cause the capping plate 20 to be moved into engagement with a container on the stationary supporting plate 21. Referring to Figure 8, it will be noted that the spring blade 108 is connected to a main conductor 125 by a lead 126 while the stationary blade 109 is connected by a lead 127 to the coil 128 of a retarded relay, the coil being connected by a lead 129 to the other main conductor 130. When the contact of spring blade 108 is moved into engagement with the contact of spring blade 109, coil 128 will be momentarily energized. However, since the relay is of the retarded type, it will not move its armature 131 into engagement with contacts 132 and 133 until a fraction of a second has elapsed, thereby insuring that the movement of the container upon the stationary supporting plate 21 is entirely completed and the container is entirely stationary before the capping head 20 begins its descent.

When relay 128 moves its armature 131 to bridge the contacts 132 and 133, it will energize one coil 134 of a double-acting relay since the contact 133 is connected to one side of coil 134 by a lead 135 and the coil is also connected by a lead 136 to the main conductor 130. The other contact 132 is connected by a lead 137 with the opposite main conductor 125. This energization of coil 134, which is only momentary, will draw an armature 138 into engagement with fixed contacts 139 and 140 but armature 138 is mechanically interlocked so as to remain in the position to which it is urged. Contact 140 is connected by a lead 141 with main conductor 130 while contact 139 is in circuit through a lead 142 with the coil 143 of the electromagnet 24 of the capping head, this coil being connected at its opposite end by a lead 144 to the main conductor 125. Energization of coil 143 will cause its armature 89 to be drawn downwardly so that the right hand end (Figure 1) of lever 84 will be drawn downwardly thereby depressing the capping plate 20.

When the right hand portion of lever 84 reaches its extreme lower position, it will engage a button 25 forming part of a switch element 25a mounted as illustrated in Figure 1, depressing the button 25 so as to cause the contact carried by the latter into engagement with a fixed contact of switch 25a. Moving contact 25 is connected by a lead 147 to the opposite coil 148 of the double-acting and mechanically interlocked relay and this coil is also connected by a lead 149 to the main conductor 130, while the fixed contact 146 is connected by a lead 150 with the opposite main conductor 125. Hence, when lever 84 depresses button 25, it will close the circuit just described, so as to energize the coil 148 to thereby return the mechanically interlocked armature 138 of the double-acting relay to the position illustrated in Figure 8, thereby de-energizing the capping head actuating coil 143 so that the springs 26 may return the capping plate 20 and armature 89 to raised position. As soon as lever 84 rises, the contact 25 will also rise, but armature 138 will remain in the Figure 8 position until coil 134 is again energized.

It will thus be observed that the capping head cannot be moved downwardly to capping position until the container is absolutely stationary upon the stationary supporting plate 21 and that as soon as it reaches full downward position, its energizing coil 143 will be de-energized so that it will be promptly returned to a raised position out of the path of the succeeding container.

Figure 2 illustrates a modified form of circuit controlling device 23a which may be placed in the Figure 8 circuit instead of the device 23 of Figures 4 and 5. In the Figure 2 form the link 98 extends through a bracket 98a into a housing 99a of the device 23a. A spring 121 positioned between a collar on link 98 and the outer wall of the housing serves to urge the link 98 to an outward position, that is, to the right in Figure 2. The inner end of link 98 bears against the free end of a lever 122 pivoted at 123 and which lever is normally held to the right by means of a leaf spring 124 fixed to the lever and having its outer end bearing upon a pin 125. The opposite end of lever 122 pivotally carries a pawl 126 urged to upward position by means of a spring 127 surrounding its pivot. This upward position is limited by a set screw 128 adjustably mounted in a lateral extension of lever 122.

The outer end of pawl 126 engages a ratchet wheel 129 which is also engaged by a second pawl 130 pivoted at 131. Pawl 130 carries a movable contact 132 normally out of engagement with a fixed spring contact 133. It will be noted from Figure 2 that movable contact 132 bears against the pivot end of lever 122 when its pawl 130 is seated in one of the pockets of the ratchet wheel and is then out of engagement with fixed contact 133. The pivot end of lever 122 thereby serves as a limit stop for movable contact 132. The contacts 132 and 133 are suitably insulated from their operating elements.

In the operation of the control mechanism 23a of Figure 2, as a container is moved from the infeed portion of supporting conveyor 11 to the position on the stationary plate 21 indicated in Figure 3, the forward and lower portion of the container will engage the roller 93 of trip 22 to move the toggle mechanism toward straightened position. As a result, the long link 95 will move to the right with regard to Figure 3, thereby moving the link 98 to the left in Figure 2. Such movement of link 98 will cause lever 122 to swing to the left and a corresponding movement will be imparted to the pawl 126. At the instant that the container entirely leaves conveyor 11 and holding device 17, the link 95 will have moved far enough to move link 98 a proper distance to rotate ratchet wheel 129 in a clockwise direction sufficient for one tooth of the ratchet wheel to move beneath the second pawl 130 and lift the same, thereby swinging contact 132 against contact 133. However, pawl 130 will immediately drop behind the tooth which has raised it and its engagement with contact 132 will thereby be broken.

The closing of the circuit between the contacts 132 and 133 will energize the retarded relay 128 as described in connection with Figure 8 so as to set up the Figure 8 circuit to move the capping element 20 downwardly to move the applied cap to sealed position after the container has reached a fully stationary position, all in the manner described in connection with Figure 8.

With the Figure 2 device 23a, when the container shown in Figure 3 moves to the right to enable the toggle mechanism to resume its normal position in the path of the next container, link 98 will return to the right causing pawl 126 to ride back and drop behind the next tooth of the ratchet wheel. The second pawl 130 will, of course, prevent the ratchet wheel from rotating in a counter-clockwise direction during the dragging movement of pawl 126 along the

ratchet wheel. Spring 124 moves lever 122 to the right as soon as the pressure on link 98 is released and the spring 127 holds pawl 126 in the upper position shown in Figure 2 though permitting it to swing downwardly sufficiently to ride back over the adjacent tooth of the ratchet wheel.

It will be understood that to adjust the machine for operation, the trip 22 will be so positioned that it will be actuated by the final movement of a container upon stationary plate 21 so that capping plate 20 will not descend until the container is absolutely stationary. The capping head will also be so positioned that it will be centrally over the container. Thus, the cap will be moved to sealed position by a force applied in an entirely vertical direction.

Figure 9 diagrammatically illustrates a modified circuit to control the operation of the capping element 20. The Figure 9 circuit may be used in place of that illustrated in Figure 8 and does not require use of the switch elements of Figures 2 and 5. In addition, it does not require use of the trip linkage arrangement illustrated in Figure 3.

Referring to Figure 9, the numeral 22a designates a trip in the form of an electrical switch, preferably of the type known as a micro switch. The switch 22a would be positioned above and to one side of the stationary container supporting plate 21 at much the same location as the toggle trip device 22 of Figure 3. This positioning of the switch 22a will result in closing of the switch by a container an instant before the container has moved entirely upon the stationary supporting plate 21 to thereby come to a stop on that plate. The movable contact element 200 of switch 22a, or at least the container engaging portion of element 200, will project toward the center line of the conveyor 11 and will be moved outwardly or away from that center line by the engagement of a container with the element.

The movable contact 200 of switch 22a is connected by a lead 201 to a source of power. A second lead 202 extends from the opposite polarity of the source of power and to the coil of electromagnet 24 which is adapted to move the armature 89 of capping head 26 downwardly. A lead 203 extends from the fixed contact 204 of switch 22a, lead 203 being connected by a short lead 205 to one end of a coil 206 of a retarded-closing relay generally designated by the numeral 207. A lead 208 connects the other end of coil 206 to the lead 202. A branch lead 209 connects the lead 203 to one contact 210 included in relay 207. A lead 212 extends from the other contact 211 of relay 207 and through the normally closed contacts of a retarded-opening relay 213 to a lead 214 connected to the coil 143 of electromagnet 24.

The retarded-opening relay 213 has its coil 215 connected by a lead 216 to lead 212 and by a lead 217 to lead 202. The armature 218 of relay 215 normally bridges the fixed contacts of this relay, while armature 219 of retarded-closing relay 207 is normally out of engagement with the contacts of that relay, all as shown in Figure 9.

The operation of the Figure 9 circuit is as follows: When a container is moving upon the container supporting plate 21, and before the container reaches a stationary position, the side wall of the container will engage the movable contact 200 of switch 22a so as to close that switch. As a result, with the armatures of the relays 207 and 213 in the position shown in Figure 9, current

will flow from one side of the power source, through lead 201, and switch 22a, lead 203, coil 206 of retarded-closing relay 207 and by leads 208 and 202 back to the power source.

Relay 207 has a retarded action of such extent that the contacts carried by its armature 219 will not be brought into bridging engagement with the contacts 210 and 211 until enough time has elapsed to enable the container to move entirely off conveyor 11 and thereby reach a stationary position on plate 21. When the contacts 210 and 211 are thus bridged, the coil of electromagnet 24 will be placed in parallel with the coil 206 of relay 207, the flow from contact 211 being through lead 212, through the bridged contacts of relay 213, lead 214, coil 143 of electromagnet 24, and lead 202 to the source of power.

As a result, the capping head armature 89 will be moved downwardly to swing lever 84 downwardly about its pivot 85 to thereby move capping element 20 down to move the cap to sealed position on the container.

At the same instant that the closing of relay 207 places the coil 143 of capping head electromagnet in parallel with the coil 206 of relay 207, the coil 215 of retarded-opening relay 213 will also be placed in parallel with the two coils just mentioned. That is, the bridging action of armature 219 will cause current to flow in lead 216, through coil 215 and lead 217. The coil 215 of the normally contact-bridging relay 213 will thereby have current flow therethrough. However, because relay 213 is also of the retarded type, the capping head 20 will descend to cap sealing position before the armature 218 of relay 217 moves away from its fixed contacts to thereby break the circuit which energizes the capping head coil 143. Obviously, when the relay 213 is fully energized, no current will flow through lead 214 to coil 143 and the spring 26 can lift the capping head to its normal position. By this time, belt 11 will move another container into contact with the container which has just been sealed so that the sealed container will be moved out of engagement with switch 22a. Therefore, switch 22a will open by spring action and the circuits through the coils 206 and 215 of the relays 207 and 215, respectively, will be de-energized so that these relays will immediately assume their normal positions shown in Figure 9.

It is to be noted that since the steam locked in the head space of a sealed container has no pressure and because the container will be surrounded by steam at a temperature identical with that of the steam sealed within the head spaces, the sealed cap has no tendency whatever to rise from sealed position when the capping head rises. This same situation holds true when the sealed container is moved off stationary plate 21 by the succeeding container and into the open atmosphere upon the outfeed portion of conveyor 11. That is, because the steam in the container head space is only at atmospheric pressure, it cannot cause the cap to lift and, therefore, no means to hold the cap sealed during cooling is required. By the present apparatus and method, the container and particularly the cap will both be simultaneously and uniformly subjected to atmospheric temperature almost immediately after capping has been performed and quick uniform cooling to contract the steam is assured.

Since the present method and apparatus insures that caps will have no tendency to rise from containers between the moment they have been moved to a sealed position and the time when

the steam condenses to create a low pressure condition in the container head space, the invention may be used with caps which are held sealed primarily by a low pressure condition as well as with caps provided with some type of locking means.

As has been indicated above, the inclusion of a vertically moving capping or sealing element in the present invention is found to be highly advantageous and a considerable improvement upon a continuously moving capping element of endless form. More particularly, while an endless capping or sealing element has the theoretical value of sealing containers at greater speed because it does not require that the movement of the containers be stopped, this theoretical advantage is altogether offset by the fact that containers may be upset or their caps either distorted or dislodged by the endless and moving element.

The capping element of the present invention, with its control so designed that the capping head cannot descend until the container is stationary, entirely eliminates all of the defects of the endless type of head. Also, since by the present invention the capping element is immediately retracted or raised so as to be out of contact with the container which has just been sealed, it is not necessary to widely space the containers delivered to the apparatus. That is, containers can be closely spaced when delivered to the apparatus because the stopping of a container for sealing is only momentary and the following container can, therefore, quickly contact with it to place it upon the outfeed portion of the supporting conveyor.

The use of a quickly operable sealing element such as provided by the present invention has the further advantage of insuring that steam will be quickly entrapped within the container head space while it is still at maximum temperature. That is, with the endless type of sealing element, the cap is only gradually applied to the container and the steam within the container head space may condense or be cooled before the sealing is entirely performed. Naturally, if any portion of the steam condenses, air may enter the head space to raise the final pressure in the container head space.

Continuously moving endless sealing elements usually extend from one end of the steam tunnel. The positioning of the present sealing element entirely within the highly heated steam chamber causes the sealing element to be maintained at a high temperature so that it cannot condense steam trapped in the container head space. In machines of the endless belt type, the belt becomes cooled, either because cooling liquid is directed upon it or because it moves into a cooler atmosphere as indicated above. Naturally, if a cap is not yet fully sealed upon the container at the time that this cooling begins, condensation of steam will occur, with a resulting higher head space pressure.

The use of a reciprocating capping element is particularly efficient in sealing caps of the type having locking lugs upon their skirts. That is, by the present invention the caps are moved directly downwardly by a straight line movement to a sealed position upon the container. Sealing apparatus of the endless belt type are particularly inefficient in applying this type of cap because such caps are more apt to become tilted upon initial contact with the sealing element due to the fact that the lugs prevent them from being

readily moved to a sealed position upon the container. For example, if a lug type cap moves adjacent the sealing element with one of its lugs resting upon the mouth of the container, it may not be subsequently properly seated by an endless sealing element, but, instead, may be bent or otherwise distorted or entirely knocked off the container. The arrangement of the present invention is therefore equally useful and efficient in applying caps of both the lug type as well as those which rely primarily upon the lowered pressure within the head space to retain them in sealed position.

As has been stated above, it has heretofore been thought that if containers were stopped for sealing, they might fall over, or at least that any liquid contents would be so disturbed as to cause spilling. Therefore, continuously moving sealing elements were believed necessary, even though such elements themselves may cause upsetting and improper application of caps and are not satisfactory for sealing lug type caps. I have discovered that the stopping of containers filled to the usual extent by movement on to a stationary plate, as opposed to the stopping of a container by the positive stopping of a driven chain or other container engaging element, with its resultant vibration, does not cause upsetting of containers or any spilling of their contents. Hence, the use of the much more practical vertically moving sealing element is made entirely feasible.

The general operation of the present apparatus and method have been described in the opening portion of this specification and the specific operation of the various elements have been described in connection with the detailed description of the construction of such elements.

The terminology used in the specification is for the purpose of description and not of limitation, the scope of the invention being indicated in the claims.

I claim:

1. In a capping apparatus, a stationary support, means to move a container onto the support, a capping head above the support, means to actuate the capping head comprising a trip adapted to be moved by a container, and an electrical circuit including a retarding device, said circuit operatively connecting the trip and capping head so that the operation of the capping head by the circuit will be delayed until the container has reached a stationary position on said support.

2. In a capping apparatus, a container support, a capping head above the container support, means to move containers onto the support, and means to actuate the capping head comprising a trip adapted to be moved by a container, a reciprocable member operatively connected to the trip, a pair of electrical contacts associated with said member, a pawl pivoted on said member, and means to hold said pawl against movement about its pivot during movement of said member in one direction whereby it will move one of said contacts into engagement with the other during such movement.

3. In a capping apparatus, a container support, a capping head above said container support, and means to actuate said capping head comprising a trip adapted to be moved by a container, a link connected to said trip, a pivoted lever having its free end in contact with said link, a pawl carried by said lever, a ratchet wheel adapted to be rotated by reciprocatory movement of said pawl, a second pawl engaging said ratchet wheel, an electrical contact carried by said sec-

ond pawl, and a fixed electrical contact adapted to be engaged by said first contact during rotation of said ratchet wheel.

4. In a capping apparatus, a container support, a capping head above the container support, means to move containers onto the support, and means to actuate the capping head comprising a trip adapted to be moved by a container, a movable member operatively connected to the trip, a pair of electrical contacts associated with said member, a pivoted pawl carried by said member, and means to hold said pawl against movement about its pivot during movement of said member in one direction whereby it will move one of said contacts into engagement with the other during such movement.

5. In a capping apparatus, a base including a container support, a substantially horizontal link pivoted adjacent one end to said base, means to move the opposite end of said link downwardly, a capping head reciprocable in said base, means to urge said capping head upwardly, a resilient operative connection between said capping head and the intermediate portion of said link, a container contacting plate on the underside of said capping head, and spring means to urge said plate downwardly, said plate having its entry end beveled in a vertical plane and downwardly toward its outfeed end to level caps upon containers moving beneath the same.

6. In a container capping apparatus, a fixed supporting plate, conveyor means to deliver containers to the plate, a capping element above said plate, and capping element actuating means controlled by movement of a container onto said plate, said actuating means including means to retard actuation of the capping element sufficiently that the latter will not contact with the container cap until the container is stationary on said plate.

7. In a capping apparatus, a support upon which a container is adapted to stand stationary, means to move the container onto the support, a vertically reciprocating capping head above the container support, a capping head controlling trip above and movable with respect to said support and normally arranged in the path of movement of a container onto said support, said movable trip having a predetermined stroke carrying it out of the path of movement of the container upon contact of a container therewith, and means to retard capping movement of the capping head until the container is stationary on said support and said trip has been given its full stroke by the container.

8. In a capping apparatus, means to move a container to a stationary position, a capping element, an electromagnet to actuate said capping element to container sealing position, and means to energize said electromagnet including an electrical switch adapted to be contacted by a container, and a retarded-action relay.

9. In a capping apparatus, means to move a container to a stationary position, a capping element, an electromagnet to actuate said capping element to container sealing position, means to energize said electromagnet including an electrical switch adapted to be contacted by a container and a retarded-action relay, and means to deenergize said electromagnet including a second retarded-action relay.

10. In a capping apparatus, means to move a container to a stationary position, a capping element, an electromagnet to actuate said capping element to container sealing position, and means

to control said electromagnet comprising a normally open switch in series with the coil of a relay so that closing the switch will energize said relay, said electromagnet being in parallel with the coil of said relay through the relay contacts when said relay is energized, said relay being of the retarded type whereby the electromagnet will not be energized to operate said capping element until an interval after a container closes said switch.

11. In a capping apparatus, means to move a container to a stationary position, a capping element, an electromagnet to actuate said capping element to container sealing position, means to control said electromagnet comprising a normally open switch in series with the coil of a relay so that closing of the switch will energize said relay, said electromagnet being in parallel with the coil of said relay through the relay contacts when said relay is energized, said relay being of the retarded type whereby the electromagnet will not be energized to operate said capping element until an interval after a container closes said switch, a second relay having its coil in parallel with the coil of said first relay through the contacts of the latter when said first relay is energized, said second relay normally closing the circuit between said first relay and said electromagnet, so that energization of said second relay will de-energize said capping element actuating electromagnet, said second relay being of the retarded type so that said electromagnet will not be de-ener-

gized until after the capping element has moved to container sealing position.

12. A container capping apparatus of the character described in claim 6 wherein the conveyor means includes an element to center and grip the containers only during their movement therewith.
